(57) **CLAIM**

The ornamental design for a hub centerpiece for Mexican train dominoes, as shown and described.

DESCRIPTION

FIG. 1 is a top perspective view of a hub centerpiece for Mexican train dominoes showing my new design;

FIG. 2 is a front plan view thereof;

FIG. 3 is a back plan view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of the hub centerpiece for Mexican train dominoes shown with dominoes.

The broken lines in the drawings depict portions of the hub centerpiece for Mexican train dominoes and form no part of the claimed design. The broken lines showing dominos in FIG. 8 are for the purpose of illustrating environmental subject matter and form no part of the claimed design.

1 Claim, 6 Drawing Sheets
